Grosvenor N. Allen, Oneida, Mary Parker Fleming,
Snyder, and Lloyd E. Ressegger, Oneida, N. Y., assignors to Oneida Ltd., Oneida, N. Y., a corporation of New York

Application January 16, 1941, Serial No. 98,118

Term of patent 14 years

To all whom it may concern:

Be it known that we, Grosvenor N. Allen, citizen of the United States, residing at Oneida, county of Madison, State of New York, Mary Parker Fleming, citizen of the United States, residing at Snyder, county of Erie, State of New York, and Lloyd E. Ressegger, citizen of the United States, residing at Oneida, county of Madison, State of New York, have invented a new, original, and ornamental Design for a Spoon or Similar Article, of which the following is a specification, reference being had to the accompanying drawing, forming a part thereof, in which—

The essential feature of our new design is the ornamentation on the handle of the spoon or similar article.

We claim:

The ornamental design for a spoon or similar article, substantially as shown and described.
